UNITED STATES PATENT OFFICE

PAUL J. HENRY, OF LONG ISLAND CITY, NEW YORK

AIRFOIL

Application filed December 31, 1930. Serial No. 505,680.

This invention relates to airplanes and my improvements are directed to a supporting airfoil of composite character, having parts which are movable for the purpose 5 of enabling the airfoil to have the form either of a low incidence, high speed element, or of a high incidence, low speed element.

With these and other objects in view I have devised a supporting airfoil having a fixed main or forward portion, and a rearward portion that is pivotally supported to be movable with relation to the main portion for increasing the camber of the airfoil. Also, there is a gap provided between 15 the airfoil portions for the flow of air to establish communication between a region of high pressure and one of low pressure, and thereby impart additional energy to the upper surface, thus helping to maintain 20 smooth flow over the upper surface and thereby increase the lift.

Also the rearward portion is divided into an upper member, which is either fixed or balanced, and a lower pivoted member that 25 is movable to increase the camber of the airfoil, said upper member, when separated from the lower member, presenting its entering edge to the flow of air through the gap from the pressure side.

Still further my invention comprehends an airfoil that is recessed at its rearward, under surface and provided with a pivoted portion which normally fills the recess, except for a space lying between the leading edge of said pivotal portion, and the front wall of the recess, said pivotal portion being 30 movable to increase the camber of the airfoil and at the same time creating a gap for the flow of air between the rearward, under surface of the airfoil and said pivotal portion; means being provided for closing the gap when the pivotal portion lies within the recess and the airfoil thereby has normal 35 contour.

An important advantage of my invention consists in the method of dividing the trailing edge and pivoting the rearward portion to increase the camber of the lower surface 40 without disturbing the boundary layer of the upper air stream. In ordinary flap prac-

tice the upper and lower surfaces of the flap constitute the rear portion of the profile section used and when the flap is depressed the air is forced to bend around and down over the upper surface of the flap, and the 55 air stream, being unable to do this except at the smallest angles of depression, breaks away in eddies with a loss of lift and a rapid increase in drift, thereby causing a stalled condition. 60

Other features and advantages of my invention will hereinafter appear.

In the drawing:

Figure 1 is a diagrammatic, side view of a supporting airfoil, comprising a main front 65 portion, a pivotal rear under portion, and a balanced rear upper portion, the airfoil portions here being disposed in their relation as composing the airfoil in its low incidence, high speed attitude. 70

Fig. 2 is a similar view with the airfoil portions disposed in their relation as composing the airfoil in its high incidence, low speed attitude.

Fig. 3 is a view corresponding with Fig. 75 2, excepting that here the rear upper portion is fixed instead of balanced, and

Fig. 4 illustrates a modification wherein a rear under portion is movable into and out of a recess formed in the airfoil. 80

While my invention is applicable with supporting airfoils of different types I have herein illustrated my improvements in conjunction with a Clark Y airfoil, whose main, forward portion in the example of Figs. 1 and 85 2, is indicated by the reference numeral 1, said portion having a rearward concavity 2 that continues downwardly and forwardly into a convexity 3 that meets the lower pressure surface 4. 90

Opposed to the concavity 2 is the convexed nose or leading edge 5 of a rearward airfoil portion 5, which is pivotally supported, as at 7, the pivot being about in the centre of pressure of said portion 6, or forwardly thereof; 95 the nose 5 being spaced from the concavity 2 to provide an intervening gap 8 that is maintained throughout the pivotal movement of portion 6, such movement carrying portion 6 between the attitudes thereof shown in Figs. 100

1 and 2 with relation to the main portion 1.

The upper surface of airfoil portion 6 has a depression 9 therein, adapted to seat an airfoil element 10 that is movably supported as by a pivot 11, toward its forward end, so that said element may be balanced by the air flow it encounters when separated from portion 6.

In the assembled or conjunctive state of portions 1 and 6 and element 10, seen in Fig.

10 1, they unite to constitute the airfoil in its attitude of low incidence for high speed, the rear ends of portion 6 and element 10 forming the trailing edge of the airfoil. In this state the flow of air from the pressure surface 15 4 passes through the gap 8 and adds to the lift efficiency of portion 6 and its associated element 10.

When however the portion 6 has been 20 swung downwardly on its pivot 7, as by control means (not shown) manipulated by the pilot into the position seen in Fig. 2, then the element 10 divides the airflow, being balanced thereby, and the angled portion 6 accords the airfoil high lift, slow speed characteristics, with steep gliding combined with 25 moderate vertical rate of descent, without necessitating an excessive inclination of the fuselage or passenger compartment.

In Fig. 3 there appears an airfoil corresponding with that shown in Figs. 1 and 2 in 30 all respects, except that in Fig. 3 the element 12 is fixedly supported, instead of being pivoted like the similar element 10 of Figs. 1 and 2.

35 The airfoil 13 appearing in Fig. 4 differs from the foregoing in that it comprises a continuous structure, from entering edge 14 to trailing edge 15, but is recessed in its under, rearward surface, as at 16, and adapted to 40 contain, in the recess, a lower, rearward portion 17, that is pivotally supported, as at 18, said portion normally completing the airfoil profile in its low incidence, high speed attitude and serving, when swung downwardly, as shown in dotted lines, to increase 45 the camber of the airfoil, for low landing speed.

The leading edge or nose 19 of the portion 50 17 is opposed to the forward wall 20 of recess 16 across an intervening space 21, a hinged flap 22 normally closing the entrance to space 21. But when the airfoil portion 17 is swung downwardly, as shown in dotted lines, to increase the camber of the 55 airfoil, then a gap 23 is created between the nose 19 and the opposed surface of recess 16, and air will flow through the gap from the pressure surface of the airfoil, this air flow causing the flap 22 to uncover space 21 60 and exerting pressure against the surface of recess 16.

The movable portions of the airfoil may 65 extend throughout the entire span thereof, or be limited to any desirable portion thereof.

Lateral control of an airplane provided

with my improved supporting airfoil has not been considered herein, because any desirable method of lateral control may be employed therewith without affecting the principle involved in my invention.

Variations within the spirit and scope of my invention are equally comprehended by the foregoing disclosure.

I claim:

1. A supporting airfoil having a recess in 75 its under surface, the top of said recess being contoured like the upper surface of an airfoil, and a pivotal airfoil member located at the rearward half of said supporting airfoil and normally lying snugly within said recess, 80 against the top thereof, the nose of said pivotal airfoil being opposed to the forward wall of the recess over an intervening space, and the pivot being distanced rearwardly from said nose whereby the upper surface of said pivotal airfoil recedes from said recess to form a passage as said pivotal airfoil is 85 swung downwardly to increase the camber of the airfoil.

2. A supporting airfoil having a recess in 90 its under surface, the top of said recess being contoured like the upper surface of an airfoil, a pivotal airfoil member located in the rearward half of said supporting airfoil and normally lying snugly within said recess, 95 against the top thereof, the nose of said pivotal airfoil being opposed to the forward wall of the recess over an intervening space, and the pivot being distanced rearwardly from said nose whereby the upper surface of said 100 pivotal airfoil recedes from said recess to form a passage as said pivotal airfoil is swung downwardly to increase the camber of the airfoil, and a hinged flap to normally close said intervening space.

New York, N. Y., December 29th, 1930.

PAUL J. HENRY.
